UNITED STATES PATENT OFFICE.

PET THOMAS WOLPERT, OF ATLANTA, GEORGIA.

TOY ROUNDABOUT.

1,240,285.

Specification of Letters Patent. Patented Sept. 18, 1917.

Application filed November 15, 1916. Serial No. 131,494.

To all whom it may concern:

Be it known that I, PET THOMAS WOLPERT, a citizen of the United States, residing at Atlanta, in the county of Fulton and State of Georgia, have invented a new and useful Toy Roundabout, of which the following is a specification.

The device forming the subject matter of this application is a toy of the roundabout type, and adapted to be manufactured in a comparatively small size, the rotatable element of the structure carrying swings in which figures are seated. By turning the rotatable element of the structure in one direction, a spring is put under tension, and when the rotatable element is released, this spring reacts and causes a rotation of the member which carries the swing.

One object of the invention is to improve a structure having the characteristics above noted.

Another object of the invention is to provide a device of this type which can be knocked down and set up readily.

The invention aims to improve the suspension elements which carry the swings and to give to said elements new and added functions.

The invention aims to improve the swing construction in relation to the figures which are seated in the swings.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings,

Figure 1 shows in elevation, a toy constructed in accordance with the present invention;

Fig. 2 is a top plan wherein sundry parts have been omitted for the sake of clearness;

Fig. 3 is a cross section taken on the line 3-3 of Fig. 1 and showing the frame portion of the device in top plan;

Fig. 4 is a vertical section taken approximately on the line 4-4 of Fig. 3, parts appearing in elevation;

Fig. 5 is a cross section taken approximately on the line 5-5 of Fig. 4; and 55

Fig. 6 is a perspective view showing the lower portion of one of the swings.

In carrying out the present invention there is provided a frame including a base made up of rectangularly disposed cross bars 1 provided intermediate their ends with interengaged notches 2. Superposed on the cross bars 1 at their place of intersection is a wear plate 3 which is made of metal. A block 4 is superposed on the wear plate 3 and is provided with a recess 5. Securing elements 6 pass downwardly through the block 4 and through the wear plate 3 and enter the cross bars 1, to hold all of the parts above described together. The frame above 70 mentioned includes a cap 7 which preferably is of a frusto-pyramidal form, including side walls and a top. In the top of the cap 7, slots 8 are formed. The top of the cap 7 has a central opening 9 of circular 75 contour. Legs 10 pass upwardly through sockets 11 on the cap 7, and have upstanding tongues 12. The upper ends of the legs 10 are disposed inside of the cap 7, as shown in Fig. 4. The tongues 12 pass upwardly 80 through the slots 8 in the top of the cap 7 and are bent down on the top of the cap, in a manner which will be manifest when Figs. 3 and 4 are examined. The foregoing construction embodies a novel and useful means 85 whereby the legs 10 may be detachably assembled with the cap 7. Secured to the lower ends of the legs 10 are strips 14 which may be made of metal, the strips 14 being united by attaching elements 15 with the 90 cross bars 1 of the base near to the outer ends of the cross bars.

The rotatable element of the structure includes a shaft 16 the lower end of which is received for rotation in the recess 5 of the block 4 of the base. The lower end of the shaft 16 is provided with a thrust bearing 17 which engages the wear plate 3. The thrust bearing 17 preferably is made of metal and is of bluntly pointed form, the co-operation between the parts 17 and 3 resulting in a reduction of friction. The shaft 16 passes through the central opening 9 in the cap 7 and is journaled therein. The upper end of the shaft 16, denoted by the numeral 100 18, is of rectangular cross section. A flag

19 may be mounted in the upper end of the part 18 of the shaft. The rotatable member of the device includes a pair of rectangularly disposed top bars 20, notched together intermediate their ends as shown at 21, after the manner of the cross bars 1 of the base. At their point of crossing, the top bars 20 are provided with squared sockets 22 receiving the part 18 of the shaft 16, so as to connect the shaft and the top bars for simultaneous rotation. Hooks 23 are loosely attached to one of the top bars 20, to wit, to that cross bar which passes beneath the upper cross bar, near the place where the cross bars intersect. The hooks 23 are adapted to engage with keepers 24 on the squared portion 18 of the shaft 16. The hooks 23 support the top bars 20 so that they will swing clear of the upper ends of the tongues 12 which, it is to be recalled, are bent down on top of the cap 8. When it is desired to take the structure apart, the top bars 20 are slid upwardly off the squared portion 18 of the shaft 16, the hooks 23 having first been disengaged from the keepers 24. Recalling that one of the objects of the invention is to provide a structure which can be taken down and set up readily, the feature last above mentioned is of importance. Surrounding the shaft 16 is a helical spring 25. The upper end of the spring 25 is detachably connected with an eye 26 carried by the shaft 16. The lower end of the spring 25 is detachably connected, as shown in Fig. 5, with an eye 27 mounted in the block 4. It will be obvious that when the shaft 16 is rotated in one direction by hand, through the medium of the top bars 20, the spring 25 will be put under tension, and when the rotatable member comprising the shaft 16 and the top bars 20 is released, the spring 25 will react, to cause a rotation of the shaft 16 and parts carried thereby, the device thus operating as a spring actuated roundabout. The squared portion 18 of the shaft 16 near to its upper end is provided with openings 28. The top bars 20 of the rotatable member are provided near their ends with outer openings 29 and with inner openings 30. Flexible elements 31 are extended through the openings 28 in the upper end of the shaft. The flexible elements 31 are extended downwardly through the openings 29 in the top bars 20, and are upwardly extended to form loops, the ends of the flexible elements 31 entering the openings 30. The loops thus formed are denoted by the reference character 32. Wedges 33 are inserted into the openings 28 in the shaft and in the openings 29 and 30 of the top bars to hold the flexible elements 31 in place. Those portions of the flexible elements 31 which lie between the top bars 20 and the upper end 18 of the shaft constitute guys, sustaining the bars 20 at their outer ends. The construction is such that a single flexible ele-

ment is made effective to form, at once, a pair of guys and a pair of flexible loops adapted to constitute swings as hereinafter set forth. The wedges 33 may be removed at any time, thus permitting the flexible elements 31 to be detached, a knocking down of the structure being facilitated in this way. A rim 34 engages the ends of the top bars 20 and is secured thereto by attaching elements 35. The rim 34 preferably is a strip of flexible material, which may be rolled up tightly in spiral form, to facilitate the storing of the device in small compass. The rim 34 serves as a connection between the ends of the top bars 20, to some extent, but it is of use mainly in supporting festoons 36, or similar decorations. Those portions of the flexible elements 31 which extend between the squared upper end 18 of the shaft 16 and the outer ends of the top bars 20 may be similarly decorated if desired.

The loops 32 support seats 37 having openings 38 through which the side portions of the loops pass. Assembled with each seat 37 is an angular back bar 39, to the upper end of which a U-shaped strip 40 is secured. The ends of the strip 40 are provided with reduced extensions 41 terminating in eyes 42 which engage the side portions of the loops 32. Projecting inwardly from the extensions 41 are tongues 43. The tongues 43 are connected by a tie 44 which may be a cord or a piece of wire. Dolls 45 occupy the seats 37, the U-shaped strip 40 and the tie 44 inclosing each doll. In order to retain the dolls 45 in an erect and natural posture, rings 46 extend around the necks of the dolls 45 and inclose the side portions of the loops 32.

The operation of the structure has been set forth hereinbefore, step by step, but by way of résumé, it may be stated that the rotatable member may be turned manually by means of the top bars 20 to put the spring 25 under tension, and when the rotatable member is released, the spring will react and cause the rotatable member to turn, carrying with it the swings 32-37 and the dolls 45 seated thereon. A review of the various features hereinbefore described will make it evident that the device as an entity is so constructed that it may be set up and taken apart readily.

Having thus described the invention, what is claimed is:

1. A toy of the roundabout type, comprising a frame including a base, a cap having side walls provided with sockets and a top, the top being equipped with openings, legs extended through the sockets and secured at their lower ends to the base and having their upper ends disposed within the side walls, and tongues carried by the legs, the tongues extending through the openings, and being clenched on the top.

of the cap; and a rotatable member including a shaft journaled in the top of the cap and in the base.

2. A toy of the roundabout type, comprising a frame embodying a base, a cap and legs connecting the base and the cap; a rotatable member including a shaft journaled in the base and in the cap; a spiral spring surrounding a portion of the shaft in a plurality of vertically superposed convolutions; means for securing the upper end of the spring to the shaft; and means for securing the lower end of the spring to the base.

3. In a toy of the roundabout type, comprising a rotatable member including crossed top bars, the top bars being equipped with a polygonal recess at their point of crossing; a shaft including a polygonal portion fitting in the recess, and a circular portion; a frame in which the circular portion of the shaft is journaled; and means for releasably connecting one of the top bars with the polygonal portion of the shaft, at a point above the top bars, thereby to suspend the top bars on the polygonal portion of the shaft to enable the top bars to clear

the upper end of the frame, and to maintain the polygonal portion of the shaft engaged with the polygonal recess of the cross bars. 30

4. A toy of the roundabout type comprising a frame; a shaft journaled in the frame and provided with an opening adjacent its upper end; a top bar carried by the shaft and provided adjacent its ends with inner and outer openings; a flexible element extended through the opening in the shaft and extended downwardly through the outer openings in the cross bar, the ends of the flexible element being extended upwardly through the inner openings in the cross bar to form loop-shaped swings; and securing devices coöperating with the openings and with the flexible element to prevent a movement of the flexible element in 40 45

In testimony that I claim the foregoing as my own, I have hereto affixed my signature in the presence of two witnesses.

PET THOMAS WOLPERT.
